UNITED STATES PATENT OFFICE.

ABRAM C. MOTT, JR., OF PHILADELPHIA, PENNSYLVANIA, ASSIGNOR TO ABRAM COX
STOVE COMPANY, OF PHILADELPHIA, PENNSYLVANIA, A CORPORATION OF PENN-
SYLVANIA.

MOLDING-MACHINE.

Specification of Letters Patent.

Patented June 27, 1916.

1,189,163.

Application filed January 28, 1913. Serial No. 744,728.

To all whom it may concern:

Be it known that I, ABRAM C. MOTT, Jr., a citizen of the United States, residing in Philadelphia, Pennsylvania, have invented certain improvements in Molding-Machines, of which the following is a specification.

One object of my invention is to improve the construction of molding machines in which one part of the mold swings on a pivot and another part is adapted to a yielding, vertically movable table.

A further object of my invention is to provide means for locking the table in the position to which it is adjusted.

The invention also relates to certain improvements in the stops for the pattern board.

In the accompanying drawings:

Figure 1 is a side view of my improved molding machine; Fig. 2 is a plan view; Fig. 3 is an enlarged inverted plan view showing the mechanism for locking the table; Fig. 4 is a sectional view on the line *a-a*, Fig. 3; the operating arm being in full lines; Fig. 5 is a sectional view on the line *b-b*, Fig. 3; Fig. 6 is a perspective view of the lever for raising and lowering the table; Fig. 7 is a perspective view of the latch; Figs. 8 and 9 are perspective views of the pivoted pattern board supports; Fig. 10 is a perspective view of one of the adjustable carriers for the pattern board supports; Fig. 11 is a perspective view of the clasp for holding the two parts of the flask together; Fig. 12 is a sectional view of the two flasks, showing the sand supporting plates projected; and Fig. 13 is an enlarged plan view showing one of the levers and portions of the sand supporting plates.

Referring to the drawings, 1 is the frame of the molding machine, having sockets 2 for the spindles of casters 3; although it will be understood that in some instances the frame may be mounted on stationary supports.

4 are the standards on which is mounted the pivoted shaft 5 for the head 6 which consists of two side members connected together by a rod. Secured to the head are brackets 7 to which the upper portion 8 of the flask is secured.

9 is a spring attached to the cross rod of the head 6 and to a rod at one end of the frame. The point of connection of the spring to the head has such relation to the

shaft 5 that it will tend to counterbalance the flask when it is moved from one position to the other. When the flask is turned back from the position illustrated in Fig. 1, it rests upon the supports 10.

11 are handles which are secured to the flask 8 on the side opposite to the brackets 7 and are used to turn the flask on its pivot 5. The brackets 7 are vertically adjustable on the head 6. Each side member of the head has a vertical rib extending into a vertical slot in the bracket.

13-13 are bolts which pass through slots 12 in the side member of the head, securing the brackets in any position to which they are adjusted.

19 is a carrying frame mounted in suitable guides on an extension 14 of the main frame 1. The carrying frame consists of two side members 50 and a connecting cross member 51 and tie rods 52. The side members have sockets 22 at each end and adapted to the sockets are plungers 23, supported by springs 24 in the sockets. At the center of each side member is a post 18 which extends to a point directly above a transverse shaft 15 mounted in bearings in the extension 14 of the frame 1. The shaft 15 has two cams 17 on which rest the posts 18.

16 is a hand lever for turning the shaft 15 to raise and lower the frame 19. On one of the posts is a latch 20 arranged to engage a projection 21 on the hub of the lever 16 and on the shaft 15, and is for the purpose of locking the shaft when the cams 17 are in the elevated position. By releasing the latch, the handle can be turned in the direction of the arrow so as to lower the frame 19 which carries the bottom board and the lower section of the flask.

25 is the table which is supported by the plungers 23 and upon which rests the bottom or follow board 26.

27 is the drag or lower portion of the flask, and 8 is the cope. Mounted between the two sections 8 and 27 of the flask is the pattern board 29.

In order to retain the plungers 23 in the position to which they are adjusted, I provide means for locking the four plungers by the operation of a single lever.

30 are sliding bolts which are adapted to openings in the sockets 22 and are also adapted to openings in a flange 31 of a plate secured to the frame 19 at the center, as

shown in the inverted plan view, Fig. 3. The ends of the bolts can be forced directly against the plungers 23 and thus hold them rigidly in the position to which they are 5 adjusted. The opposite end of each plunger bears against a spring 32 within a flange 31, and a cam 33 has four cam surfaces resting against the springs. The cam 33 is secured to an operating arm 34 projecting at one 10 end of the machine, so that when the operating arm is turned in one direction the bolts 30 are forced against the plungers and when the arm is turned in the opposite direction the cams will release the plungers 15 and will allow them to move.

Mounted on slides 37, Fig. 10, at each side of the machine, are stops 35 and 36 for the pattern board 29. Each slide is slotted, as shown, for the reception of the lower end 20 of the stop 35 and as this stop is provided with a nut, it can be adjusted in the slot to any position desired. The stop 36 is pivoted at 38 to the end of the slide and has a balance weight 39 so that its normal position will be 25 upright. But, when it is wished to remove the flask, the stop will swing clear of the flask. When the flask is in position both stops will be in line with the pattern board, so that when the table is lowered, the pattern 30 board will rest on the ends of the stops and upon continuing the downward movement of the table the lower flask 27 will be moved away from the pattern board.

53, 53 are levers for operating the sliding plates 54 and 55, which can be moved so as to project into the opening in the cope 8, retaining the sand after it has been packed in the cope. By moving the levers in the opposite direction the plates can be 35 retracted so as to be back of the side walls of the cope to allow for the removal of the same from the molded sand. The several plates are slotted at 54^a for the reception of the pins 54^b on the cope and the side plates 40 45 54 are recessed at each end, as shown in Fig. 13, to receive projections 55^a on the end plates 55 so that when motion is imparted to the side plates 54 the end plates must be moved with them. Each lever 53 is ful- 50 crumed to the cope and one arm of the levers is connected directly to one of the sliding plates 54 and the other arm is indi- 55 rectly connected to the sliding plates 54 by a bar 56.

55 While I prefer to employ the particular sand retaining slides and operating means therefor as shown and described, said specific devices are not my invention, and it is manifest that the slides may be constructed and operated in various other ways known to those skilled in the art, for example, as shown in United States Letters Patent No. 1,081,251, issued to me December 9, 1913, for a molding flask.

65 40-40 are centering pins on the lower

section 27 of the flask and adapted to openings in the upper section 8. These pins also pass through openings in projections on the pattern board so as to hold the pattern board and the two sections of the flask 70

41-41 are the clamps which lock the two flasks together and to the bottom board 26. These clamps are pivoted at 42 and have handles 43 and projecting hooks 44 which 75 engage the board 26. A spring 45, carried by each clamp, bears upon the frame of the flask with sufficient pressure to frictionally hold the clamps in the position to which they are adjusted.

80 The operation of the molding machine is as follows:—In making the mold, the cope 8 is turned back and rests upon the support 10. The pattern board 29 is then placed in position within the drag; the 85 flask 27 being placed in position on the pattern board. This drag 27 is then filled with sand and rammed, after which the bottom board 26 is placed on the flask and the clamps 41 applied. The entire flask is then 90 turned over on to the table 25; the bottom board resting upon the table. The levers 53 are moved so as to project the sand supporting plates into the flask, see Fig. 12, after which the cope 8 is filled with sand and 95 rammed. The clamps 41 are then released and the handle 16 turned so as to lower the table, and, as the table descends, it carries with it the bottom board 26, the drag 27, and the pattern board 29. The movement of the 100 pattern board 29 is limited as it comes in contact with the ends of the stops 35 and 36, and the drag 27 continues its movement with the table. After the drag has reached the limit of its movement and is supported 105 at the four corners, the table is locked by moving the operating lever 34 which throws the locking bars 30 into frictional contact with the plungers 23. The cope 8 is turned on its pivot clear of the pattern carried by 110 the pattern board 29 and as the pattern board has been freed from the mold within the drag 27, it is carefully raised and removed, after which the cope 8 is again turned over on to the drag 27 and the arm 34 115 is actuated so as to release the plungers 23 and the lever 16 is turned so as to raise the table, bringing the drag 27 in contact with the cope 8. The levers 53, controlling the sand retaining plates, are then actuated so 120 as to retract the plates. When this has been done, the cope 8 is again turned on its pivot, the sand remaining on the sand mold in the drag 27. Then the drag 27 is removed from its sand mold, leaving both sections of the mold on the bottom board 26, which is then removed to the pouring floor 125 and the above operation is repeated.

I claim:

1. The combination in a molding machine, 130

- of a main frame; a carrying frame mounted thereon; four plungers in the carrying frame; a table resting on the plungers; a spring mounted under each plunger; a cam pivoted to the center of the carrying frame; an operating arm for the said cam; rods guided in the frame and adapted to bear against the plungers; a spring mounted on the frame between the cam and the end of each rod so that when the operating lever is turned, the cams will press the springs against the rods in order to force said rods into frictional contact with the plungers. 70
2. The combination in a molding machine, of a main frame; a carrying frame mounted in guides on the main frame; means for raising and lowering carrying frame in said guides; a table; plungers on carrying frame for supporting the table; means for locking the plungers to the frame; a head pivoted to the main frame; brackets on the head; a cope flask rigidly secured to the brackets; a drag flask; a bottom board; clamps pivoted to the cope and adapted to engage the bottom board. 75
3. The combination in a molding machine, of a flask having a cope and a drag; clamps pivoted to the cope and having hooked ends arranged to engage the bottom board; a segmental spring for each clamp having its ends secured to said clamp on each side of the pivot, the spring being in frictional contact with the cope so that the clamp is held in the position to which it is adjusted. 80
4. The combination in a molding machine, of a main frame; a pivoted head mounted thereon; a flask; means for securing flask to the head; a carrying frame adjustably mounted on main frame; means for adjusting the carrying frame; a table supported on the carrying frame; a pattern board; stops on each side of the table to limit the movement of the pattern board located above the table; a slide mounted on the main frame and carrying the stops, one of said stops having a counter weight and being pivoted to the slide. 85
5. The combination in a molding machine, of a main frame; a table; means for supporting the table; stops on each side of the table for limiting the movement of a pattern board when mounted on said table; a slide mounted at each side of the main frame; one set of stops being longitudinally adjustable on the slides; the other stops being pivotally mounted thereon and each having a counterbalance. 90
6. A pivoted clamp for securing a flask to a bottom board, said clamp having a pivot and having a U-shaped spring secured at its ends to the clamp at each side of the pivot, so that when the clamp is in place the spring will bear against the flask and frictionally hold the clamp in the position to which it is adjusted. 95
7. In a machine of the character set forth, the combination of a pair of flask sections, means pivotally supporting one of said flask sections, supporting devices on opposite sides of such pivotal support, a match plate detachably inserted between the flask sections, posts projecting above the supporting device on one side of the machine and adapted to be engaged by the match plate, and means for raising and lowering the last mentioned supporting device. 100
8. In a machine of the character set forth, the combination of a pair of flask sections, means pivotally supporting one of said flask sections, means for detachably connecting the flask sections, a match plate removably inserted between said sections and projecting beyond the same, a platform on one side of the pivotal support for the flask, means for raising and lowering said platform, and vertically adjustable posts adapted to engage the said match plate when the platform and the flask section supported thereby are lowered. 105
9. In a machine of the character set forth, the combination of a base, a flask section pivotally mounted on an intermediate portion of the base, a second flask section, means for detachably connecting said flask sections, a match plate removably inserted between said sections and projecting beyond the same, a platform on one side of the pivotal support for the flask, means for raising and lowering said platform, and vertically extending posts adapted to engage the said match plate when the platform and the flask sections supported thereby are lowered. 110
10. In a machine of the character set forth, the combination of a base, a cope pivotally supported from an intermediate portion of the base, a drag, a bottom board for said drag, a match plate adapted to be applied between the cope and the drag and projecting beyond the outer peripheries thereof, means for detachably connecting the drag and bottom board to the cope, a platform on one side of the pivotal support, means for raising and lowering said platform, a supporting device on the opposite side of such pivotal support from the platform, and vertically extending posts grouped around said platform and adapted to engage the match plate when the platform and drag are lowered, some of said posts being pivotally supported. 115
11. In a machine of the character set forth, the combination of a cope, means pivotally supporting said cope, a drag, a bottom board for said drag, a match plate adapted to be applied between the cope and the drag and projecting beyond the outer peripheries thereof, means for detachably connecting the drag and bottom board to the cope, a platform on one side of the pivotal support. 120

- support for the cope, means for raising and lowering said platform, and vertically extending posts grouped around said platform and adapted to engage the match plate when the platform and drag are lowered, some of said posts being pivotally supported.
12. The combination of a pair of flask sections, a bottom board for one of said sections, latches pivoted to the other section and having projections adapted to engage the bottom board, and means adapted to hold said latches with the said projections in and out of operative relation to such bottom board.
13. In a machine of the character set forth, the combination of a pair of flask sections, means pivotally supporting one of said sections, a bottom board for one of said sections, latches pivoted to the other section and having projections adapted to engage the bottom board, and means adapted to hold said latches with the said projections in and out of operative relation to such bottom board.
14. In a machine of the character set forth, the combination of a cope, means pivotally supporting said cope, latches pivoted to said cope, a drag, a bottom board for said drag, arms carried by said latches and adapted to extend beneath said bottom board to support the same and the drag from the cope, and springs co-operating with said latches and adapted to hold the arms in and out of operative relation to the bottom board and the drag.
15. In a machine of the character set forth, the combination of a cope, means pivotally supporting the same, a drag, means for detachably connecting the drag and the cope, a match plate adapted to be inserted between the cope and the drag, and an adjustable sand retaining device on the lower end of the cope.
16. In a machine of the character set forth, the combination of a cope, a pivotal support therefor, a drag, a bottom board therefor, means for detachably connecting the drag and the bottom board to the cope, a match plate adapted to be inserted between the cope and the drag, a sand-retaining device at the bottom of the cope, and means for projecting said device into and removing it from the space defined by the inner walls of said cope.
17. In a machine of the character set forth, the combination of a cope, a pivotal support therefor, a drag, a bottom board therefor, means for detachably connecting the drag and the bottom board to the cope, a match plate adapted to be inserted between the cope and the drag, a sand-retaining device at the bottom of the cope, means for projecting said device into and removing it from the space defined by the inner walls of said cope.
18. In a machine of the character set forth, the combination, with a cope and a drag and means for detachably connecting the same, of a sand-retaining device interposed between the cope and the drag, means whereby said device may be projected into and removed from the space defined by the inner walls of the flask, and a pivotal support for one of the flask sections.
19. In a machine of the character set forth, the combination of the support, a sectional flask pivoted to said support, a match plate detachably inserted between the flask sections, means for separating said sections, and means adapted to receive the match plate and support the same when the flask sections are separated.
20. In a machine of the character set forth, the combination of a cope and a drag, a match plate adapted to be inserted therebetween, means for detachably connecting the cope and the drag, supporting means for the match plate vertically spaced from the peripheral portion of said plate when the cope and the drag are assembled, and means for moving the drag away from the cope a greater distance than the distance between the match plate and the supporting means.
21. In a machine of the character set forth, the combination of a cope and a drag, a match plate adapted to be inserted therebetween, means for detachably connecting the cope and the drag, supporting means for the match plate and vertically spaced from the peripheral portion of said plate when the cope and the drag are assembled, a support for the drag, and means for moving the drag support away from the cope a greater distance than the distance between the match plate and its supporting means.
22. In a machine of the character set forth, the combination of a base, a cope pivoted to an intermediate portion of the base, supporting devices on opposite sides of such intermediate support, an inwardly and outwardly adjustable sand-retaining device on the bottom of the cope, a drag, a match plate adapted to be inserted between the bottom of the cope and the top of the drag, a bottom board for said drag, latches carried by the cope and adapted to engage the bottom board, means whereby the cope and drag may be separated, and means adapted to engage the match plate and support it intermediate of the cope and drag when the latter are separated.
23. In a machine of the character set forth, the combination of a base having a platform at one side thereof and a supporting device at the other side, hollow bosses carried by said platform, springs in said bosses, posts in said bosses supported by

- 5 said springs, a central hub carried by said platform, rods projecting into the bosses and adapted to engage the posts and having their inner ends within said hub, a common 10 operating device for said rods within said hub, a flask, and means pivotally supporting said flask between the platform and the supporting device.
24. In a machine of the character set forth, the combination of a pair of flask sections, means for supporting one of said sections, a match plate inserted between said sections and projecting beyond the outer boundary thereof, a supporting base for the 15 flask, means for raising and lowering the same, means for supporting one of said sections from the other and means interposed in the path of travel of the match plate and adapted to engage the projecting portions 20 thereof as the flask is lowered.
25. In a machine of the character set forth, the combination of a pair of flask sections, a supporting device to which one of said sections is pivotally connected, a 25 match plate inserted between said sections, and projecting beyond the outer surface thereof, a platform, means for raising and lowering said platform, means detachably connecting said sections, and vertically extending posts arranged to engage the projecting portions of the match plate in the platform when the flask sections supported thereby are lowered.
26. In a machine of the character set forth, the combination of a platform, a pair 35 of flask sections, a match plate interposed between said sections and projecting beyond the outer surface thereof, vertically extending posts grouped about said platform and 40 adapted to engage the match plate when the platform and flask are lowered, and means for raising and lowering said platform, one or more of said posts being pivotally supported.
- 45 27. In a machine of the character set forth, the combination of a platform, means for raising and lowering the same, a pair of flask sections, a match plate interposed between said sections and projecting beyond 50 the outer surface thereof, vertically extending posts grouped about the platform and adapted to engage the match plate when the platform and the flask thereon are lowered, means pivotally supporting one or more of 55 said posts, and means operating to maintain the pivoted post or posts normally in vertical position.
28. In a rock-over molding machine, the combination of a tapered cope, a sand-retaining device at the bottom or enlarged end 60 of said cope, a support to which said cope is pivoted, supporting devices on opposite sides of such pivotal support, a drag, a match plate adapted to be removably inserted between 65 the cope and the drag, means for sup-
- porting the drag and match plate from the cope, means for raising and lowering the supporting device on one side of the machine, and means on such side of the machine for engaging and supporting the match 70 plate when the supporting device is so lowered.
29. In a machine of the character described, the combination of a base, an upwardly tapered cope pivotally mounted on an intermediate portion of the base, a sand-retaining device at the bottom or enlarged end of the cope, a drag, a match plate adapted to be removably inserted between the cope and the drag, a bottom board for the 80 drag, means for supporting the drag and the bottom board from the cope with the match plate in place, a platform on one side of the intermediate pivotal support, means for raising and lowering said platform, and vertically extending posts adapted to engage the match plate when the platform and the drag are lowered.
30. In a machine of the character described, the combination of a base, an upwardly tapered cope pivotally mounted on an intermediate portion of the base, a sand 90 retaining device at the bottom or enlarged end of the cope, a drag, a match plate adapted to be removably inserted between the cope and the drag, a bottom board for the drag, means for supporting the drag and the bottom board from the cope with the match plate in place, a platform on one side of the intermediate pivotal support, and means for 95 raising and lowering said platform.
31. In a machine of the character described, the combination of a base, a supporting device on each side of said base, one of said devices being vertically movable, and a cope pivoted between said devices, said cope being tapered from the bottom to the top and provided at the bottom or enlarged end thereof with an adjustable sand retaining device.
32. In a machine of the character described, the combination of a base, a supporting device on each side of said base, one of said devices being vertically movable, said base having an intermediate portion 115 between said supporting devices, a cope pivotally connected to the intermediate portion of the base, said cope being tapered from the bottom to the top and provided at the bottom or enlarged end thereof with an adjustable sand retaining device, and means adjacent to the vertically movable supporting device for engaging the match plate.
33. In a machine of the character set forth, the combination of a cope, a drag, and a match plate removably inserted therebetween, a base, means pivotally supporting the cope on an intermediate portion of the base, a support on one side of such intermediate portion whereon the cope may rest 125
- 130

while the drag is being rammed, a bottom plate for the drag, means for detachably connecting the drag and the bottom plate to the cope, a support for the drag on the opposite side of the base from the cope support and adapted to sustain the flask while the cope is being rammed, and means whereby the cope and drag may be separated and the match plate supported during such separation.

34. In a machine of the character set forth, the combination of a cope, a drag, and a match plate removably inserted therebetween, pivotal supporting means for the cope, a support on one side of such pivotal

support whereon the cope may rest while the drag is being rammed, a bottom plate for the drag, means for detachably connecting the drag and the bottom plate to the cope, and a support for the drag on the opposite side of the pivotal support from the cope support and adapted to sustain the flask while the cope is being rammed. 20

In testimony whereof, I have signed my name to this specification, in the presence of 25 two subscribing witnesses.
